Specification for Design.

Patented Apr. 20, 1920.

Application filed November 12, 1919. Serial No. 337,618. Term of patent 14 years.

To all whom it may concern:

Be it known that I, CHARLES T. WITTSTEIN, a citizen of the United States, residing at Newark, in the county of Essex and State of New Jersey, have invented a new, original, and ornamental Design for Gem-Mountings, of which the following is a specification, reference being had to the accompanying drawing, forming part thereof.

Figure 1 is a perspective view of a gem mounting embodying my invention, the

mounting being shown as set within a conventional finger ring setting shown by dotted lines, and supporting a gem also illustrated by dotted lines, and

Fig. 2 is an enlarged side elevation thereof, the setting and gem being shown in dotted lines.

I claim:

The ornamental design for a gem mounting, as shown.

CHARLES T. WITTSTEIN.
